UNITED STATES PATENT OFFICE

JOHN A. WILLIAMSON AND ALICE LOWE WILLIAMSON, OF PARSONS, KANSAS

COIN-CONTROLLED MECHANISM

Application filed October 14, 1929. Serial No. 399,558.

This invention relates to a coin controlled mechanism for permitting a member to be actuated a certain number of times, after which the member is locked against further movement, the general object of the invention being to provide a ratchet wheel, the teeth of which are engaged by the actuating means of the member, so that the wheel is rotated step by step by such actuating means, with means for locking the wheel against further rotation after the same has made a complete revolution, such locking means being moved to inoperative position by a coin deposited in a coin chute forming part of the coin mechanism.

The invention is mainly designed for use with the baseball game apparatus which was patented by us on December 14, 1915, No. 1,164,044.

This invention also consists in certain other features of construction and in the combination and arrangement of the several parts, to be hereinafter fully described, illustrated in the accompanying drawings and specifically pointed out in the appended claim.

In describing the invention in detail, reference will be had to the accompanying drawings wherein like characters denote like or corresponding parts throughout the several views, and in which:

Figure 1 is a top plan view showing a portion of the patented apparatus, with the coin control mechanism thereon.

Figure 2 is a sectional view through Figure 1.

Figure 3 is a top plan view of the coin control mechanism and the cable which operates the batter of the patented apparatus.

Figure 4 is an elevation of Figure 3, with parts in section.

Figure 5 is a view taken at right angles to Figure 4.

Figure 6 is a section on line 6—6 of Figure 3.

Figure 7 is a section on line 7—7 of Figure 3.

Figure 8 is a section on line 8—8 of Figure 3.

In these views, the letter A indicates a part of the table of the patented apparatus,

to the under side of which the lever 1 is pivoted, this lever supporting the batter B which passes through an arc-shaped slot 2 in the table, with the handle 3 of the lever also passing through an arc-shaped slot 4 in the table. The cable for operating the batter is shown at 5, it being understood that in order to cause the batter to strike at a ball, the cable must be pulled upon. These parts form part of the patented device and the present invention comprises coin operated means for limiting the number of times the cable can be pulled after a coin has been placed in the slot 6.

The improved device comprises a support C, the upwardly extending portions of which are adapted to be fastened to the under face of the table adjacent the inner end of the cable which is attached to the spring 7. A ratchet wheel 8 is rotatably supported by the support C in such a position that its teeth will engage the cable, said teeth being grooved to receive the cable. A knot 9 is formed in the cable and will engage a tooth of the wheel each time the cable is pulled upon to actuate the batter. When the cable is released, the spring 7 returns the parts to normal position and the knot 9 slides over the tooth in rear of that which has been engaged by the knot when the cable is pulled. A disk 10 is adjustably connected with the ratchet wheel through means of the arc-shaped slot 11 in the disk and the screw 12 passes through a washer 13 and through the slot into the wheel. Thus by loosening the screw, the disk can be adjusted on the wheel and by tightening the screw, the washer frictionally engages the disk and holds it in adjusted position. Said disk has an annular flange 14 thereon which is provided with a slot 15. A latch 16 is pivoted in the coin chute 6 which is formed in an upright part 17 on the support C, with the outer end of the latch adapted to engage the notch 15 to prevent rotary movement of the wheel and disk, a spring 18 acting to hold the latch in latching position. The coin chute 6 is so formed that a coin dropped into the same will drop upon the latch and then roll upon the tail end of the same, thus lifting the latch to releasing position. Then when the cable

is pulled, the knot, engaging a tooth of the wheel, will cause partial rotation of the wheel so that the notch will pass from under the latch, causing the latch to ride up the low side of the notch upon the flange so that the latch will be tilted and thus cause the coin to drop therefrom into the coin receptacle 19 hinged to the lower face of the support C. The latch is thus held in raised position by the flange 14 until the notch 15 comes under the latch after the wheel and disk have made a complete revolution so that the latch will again drop into the notch and thus prevent further movement of the ratchet wheel so that the cable cannot be actuated again until another coin has been dropped into the chute.

The ratchet wheel is shown with twelve teeth so that the player can cause the batter to strike at the ball twelve times after the insertion of a coin. Then he must insert another coin if he wishes to operate the device again. It will, of course, be understood that the wheel can be provided with as many teeth as desired.

25 While the invention is shown and described for use on the baseball game apparatus, it will, of course, be understood that it can be used on other apparatus.

It is thought from the foregoing description that the advantages and novel features of the invention will be readily apparent.

It is to be understood that changes may be made in the construction and in the combination and arrangement of the several parts, 35 provided that such changes fall within the scope of the appended claim.

What we claim is:

Coin controlled mechanism of the class described comprising a ratchet wheel, a disk 40 adjustably connected therewith, an annular flange on the disk having a notch therein, a spring actuated latch lever for engaging the notch for holding the wheel against movement and means whereby a coin inserted in 45 the mechanism will raise the lever out of the notch so that the wheel can be turned, the lever riding on the flange until the notch again comes under the same.

In testimony whereof we affix our signatures.

JOHN A. WILLIAMSON.

ALICE LOWE WILLIAMSON.
